PRESS BOX LOCKING MECHANISM

James S. Nevitt, Dallas, Tex., assignor to The Murray Company, Dallas, Tex., a corporation of Texas

Application March 21, 1935, Serial No. 12,227

5 Claims. (Cl. 100—28)

This invention relates to new and useful improvements in press box locking mechanism.

One object of the invention is to provide an improved locking mechanism for a press box 5 which is connected with and actuated by the trumper operating means, said mechanism being arranged to be applied to any type of press box of the usual construction to lock the same in position.

10 An important object of the invention is to provide an improved locking mechanism for the ordinary double press boxes which are rotatable beneath the trumper and above the press, said mechanism being so arranged that the trumper and press cannot be operated until both boxes have moved to their respective positions directly beneath the trumper and above the press, thereby eliminating the danger of said trumper and press striking the sides of said boxes and damaging the trumper or boxes due to the fact that said boxes are out of alinement; said mechanism also preventing the boxes from being moved out of position during the operation of said trumper and press.

20 Another object of the invention is to provide an improved lock for a press box including a latch member arranged to engage the box to lock it in position, and means controlled by the trumper operating means for engaging the lock member, whereby when said member is holding the box in position, said means will prevent it unlocking until the trumper operating means has been cut off to disengage said means from the member; similarly the member engaging the 30 controlling means and preventing actuating of said controlling means and the trumper operating means, when the member is in an unlocked position and the box is free to move.

25 A further object of the invention is to provide an improved lock for a press box which is connected with the control of the trumper operating means in such a way that the operation of the trumper depends on the position of said lock and the operation of said lock depends on the 35 trumper operating control.

30 A construction designed to carry out the invention will be hereinafter described, together with other features of the invention.

35 The invention will be more readily understood from a reading of the following specification and by reference to the accompanying drawings, in which an example of the invention is shown, and wherein:

40 Figure 1 is a front elevation of a double press

box, having the improved locking mechanism applied thereto,

Figure 2 is a front elevation of the lock,

Figure 3 is a side elevation of the same in its locked position, engaging the flange of the press boxes, said flange being in section,

Figure 4 is a plan view of the lock,

Figure 5 is a transverse vertical sectional view thereof,

Figure 6 is a side elevation of the upper portion of the press box, showing the trumper control means and its connection with the lock,

Figure 7 is an isometric view of the swinging latch bar and the stop bar,

Figure 8 is a schematic view of the trumper brake mechanism,

Figure 9 is an isometric view of the connection between the trumper operating shaft and the locking means shaft,

Figure 10 is a front elevation of another form of the invention,

Figure 11 is a side elevation of the same,

Figure 12 is a plan view,

Figure 13 is a side elevation of the upper end of a press box showing the connection between the lock and trumper control means, and

Figure 14 is a detail of the gear rack employed in this form.

In the drawings, the numeral 10 designates a double box press of the usual construction. Each 30 press box 11 is suitably secured on a rotatable platform 12 which is mounted to rotate within the supporting frame 13. The platform is located in horizontal alinement with the press floor 14. Each press box includes the usual side and 35 end boards 15 which are held together by the horizontal frame members 16. These members are usually located slightly above the level of the platform 12.

40 By observing Figure 1, it will be seen that the boxes 11 are arranged so that when one of said boxes is in position for charging, that is, below the trumper 17, the other box is in direct vertical alinement with the press ram plunger (not shown). With this arrangement, the cotton in one box may be tamped, while the cotton in the other box, which has already been tamped is being baled. All of the above described parts are present in the ordinary double box press and are subject to variation.

45 It has been found in practice, that when the platform is rotated to change the positions of the boxes, the trumper and ram plunger are operated before the boxes have moved to their positions in direct vertical alinement therewith. This causes 50 55

the trumper and plunger to strike the edges of said boxes, rather than entering said boxes which results in damage not only to the boxes but also to the trumper. Similarly, it has been found that 5 if the boxes are not positively locked when first positioned, they might move slightly out of alignment during the operation of the moving parts. This also causes damage to the boxes and trumper as well as delay in repairing the damaged parts.

10 To overcome these disadvantages, the locking means is directly connected with and controlled by the trumper control means. As shown in Figures 1, 6 and 8, the conventional type of control means for starting and stopping the trumper 17 and press plunger (not shown) is illustrated. This control means includes a pulley 18 which is mounted on a horizontal shaft 19 supported in suitable brackets 20 and 30 secured to the stationary frame 13. The shaft has an arm 21 (Figures 1, 6 and 8) secured thereto and this arm is connected by a link 22 to a second arm 23 secured on one end of a stub shaft 24. The shaft 24 is supported in a suitable sleeve 25 and a cam 26 is secured on its opposite end. This cam is arranged 25 to engage the outer end of a pivoted brake shoe 27 which is positioned to engage the periphery of a drive wheel 28 for operating the trumper 17. The pulley 18 is connected by any suitable means (not shown) with the operating motor of the trumper 30 17 so that when the pulley is rotated in one direction it will stop the operation of said trumper and apply the brake, and when rotated in an opposite direction it will release the brake and start the trumper. A suitable cord 28' having 35 handles 29 at each end is passed over the pulley whereby said pulley may be manually rotated.

In carrying out the invention, the shaft 19 of the pulley is extended outwardly to one end of the frame 13. (Figure 1.) The extreme outer 40 end of the shaft carries an arm 31 which is connected by a pitman rod 32 with the outer end of a horizontally extending arm 33, whereby when the shaft 19 is rotated the arm 33 is swung in a horizontal plane. The arm 33 is secured to the 45 upper end of a vertically extending rotatable shaft 34 which is located contiguous to the inner side of one of the vertical standards of the frame 13, being supported in suitable bearings 35. The lower end of the shaft is provided with a laterally extending locking bar 36 which is secured to the shaft in any suitable manner. It is obvious that when the pulley shaft 19 is rotated to start or stop the trumper, the vertical shaft 34 is rotated to swing the locking bar 36. The swinging of the 50 bar causes said bar to engage or disengage the latching means as will be hereinafter explained.

For holding the press boxes against rotation after they have been alined with the trumper and ram plunger, as has been explained, each press 55 box is provided with a bar 40, which is secured to the outer end of each box. Each bar is secured to the frame member 16 of the box and is provided with a notch 41 at the central portion of the outwardly extending flange 40' of the bar (Figure 4). 60 When the boxes are in their proper positions in alinement with the trumper and ram plunger, the notch 41 in the flange 40' on the press box above said plunger, is in alinement with the vertical standard of frame 13 and is arranged to be engaged by the latching means 42.

The latching means 42 includes a pair of angular supports 43 which are secured to the inner side of the vertical standard of frame 13. The supports are spaced apart and are mounted centrally 65 of the standard. An angular latch bar 44 is

pivoted on a pin 45 between the supports (Figures 4 and 5) and a coiled spring 46 is positioned between the vertical leg 47 of said bar and the standard, to exert its pressure to force the leg 47 outwardly at all times. The lower end of the vertical leg 47 is arranged to engage the notch 41 of each bar 40 when said notch moves opposite the same. The notch is so positioned that when said leg 47 is engaged therein, the boxes are in position beneath the trumper 17 and plunger (not shown). 10 The horizontal leg 48 of the latch is provided with ears 49 at its outer end and a vertical rod 50 is pivoted therein. The upper end of the rod is pivoted to a hand lever 51, which is mounted to swing on the inner side of the vertical standard 15 of frame 13. It is obvious that by swinging the hand lever, the latching bar may be swung to retract the lower end of the vertical leg 47 from the slot 41 of the flange 40', to the dotted line position shown in Figure 5. From the above, it is 20 obvious that as the boxes are rotated from one position to another, the latching bar 44 will engage the slot 41 of the flange moving into alinement therewith. The ends of the angle bars 40 are rounded at 40" (Figure 4) so that as said bar 25 first engages the leg 47 of the bar 44 said leg is depressed under tension of the spring 46. As soon as the notch 41 moves opposite the leg 47, said leg moves into the notch to stop further rotation. As 30 has been pointed out, the boxes are in their proper positions when this occurs.

To prevent retraction of the leg 47 from the notch 41 by the hand lever 51, the locking bar 36 on the lower end of the shaft 34 has its outer end extended over the upper surface of a lug 52 projecting upwardly from the horizontal leg 48 of the latching bar 44. When the bar 44 is engaging in the notch as shown in Figures 4 and 5, the locking bar 36 can swing over said lug to prevent upward swinging of the leg 48. This swinging occurs 40 when the pulley 18 has been rotated to turn the trumper on. If the latch 44 has not yet engaged the notch 41, then it is in a retracted position, being held so by engagement with a flange 40' of bar 40, and the lug 52 would be raised (dotted 45 lines Figure 5) directly in the path of the bar 36. In such case, the bar 36 could not be swung because of striking said lug. The halting of the bar 36 would prevent rotation of the pulley shaft 19 because of the direct connection between the 50 locking bar and said shaft. Therefore, unless the latch 44 were engaging in the notch 41 the trumper could not be turned on.

However, when the flange 40 moves away from the latching means 42, the latching bar 44 would 55 immediately swing under compression of the spring 46 so that its vertical leg 47 will be moved outward to a greater extent than when it is moved to engage in a notch 41 of one or the other of bars 40. This would move the lug 52 out of the 60 path of the locking bar 36 and permit said bar to be swung while the boxes 11 were being rotated, thereby permitting the trumper to be operated during rotation of the boxes. To avoid this, an angular stop member 53 is pivoted adjacent 65 the latch 44 on the pin 45. This member includes a horizontal leg 54 and a downwardly extending leg 55 including the angular stop member 53. A coiled spring 56 is mounted between the upper end of the leg 54 and a bracket arm 57 extending 70 upwardly from one of the supports 43, and exerts compression to force the leg 54 downwardly into the path of the swingable locking bar 36. The vertical leg 55 is provided with a laterally 75 extending arm 58 arranged to be engaged by the 75

edge of the flange 40'. By observing Figure 5, it will be seen that when the arm 58 is engaged by the flange, the stop is swung so that the leg 54 is out of the path of the locking bar 36. The 5 arm is of sufficient length to bridge the width of the notch 41 as it passes thereby. However, this bar 36 cannot be swung until the latch 44 has fallen into the notch 41. Once the locking bar has been swung inwardly and the trumper started as shown in dotted lines in Figure 4, it is below the leg 54 of the stop member, and above the lug 52 on the latch 44, and the latch cannot be retracted from the notch 41 until the bar 36 has been swung away therefrom and the trumper 10 stopped.

Assuming that the trumper is turned off, the pulley 18 is in the position shown in Figure 6, with the locking bar 36 in the position shown in full lines in Figure 4. When the bar is in this 20 position, the hand lever 51 may be swung to retract the latch 44 from the notch 41, whereby the press boxes 11 may be rotated to interchange the same. As soon as the flange 40 moves away from the latching means 42, then the stop bar 25 53 is swung compressed by spring 56, so that its horizontal leg 54 is swung into the path of the locking bar 36, thereby preventing swinging of the bar and operation of the trumper control means. At this time the latch 44 is also swung so 30 its vertical leg is extending beyond the supports 43 in the path of the flanges 40'.

The parts remain in this position until the press boxes have been rotated to opposite positions. Then the flange 40' on the press box moving into position over the ram plunger, engages the arm 58 of the stop bar 53 to swing said bar so that its horizontal leg 54 moves out of the path of the lock bar 36. However, at the same time, the latch 44 is swung inwardly so that the lug 40 52 on its horizontal leg 48 moves into the path of said locking bar 36. Thus, it is obvious that when the flange 40' swings the stop bar 53 out of the way of the locking bar 36, it also swings the latch so that the lug 52 moves into the path of 45 said locking bar. When the latch engages in the notch 41, its swinging to this engaged position moves the lug 52 out of the path of the locking bar 36 and it is then possible to swing the bar 36 inwardly between the bar 53 and latch 44 as 50 shown in Figures 3 and 5. The bar 36 is swung through the medium of the pulley 18 which also turns on the trumper 17 and ram plunger (not shown). From the above, it will be seen that the trumper cannot be operated until the boxes 55 11 are in latched position.

After the bar 36 has been swung inwardly, (dotted lines, Figure 4), the latch 44 can not be swung by swinging the hand lever 51, because said bar overhangs and engages the upper edge 60 of the lug 52 thereon. Therefore, the latch cannot be retracted from the notch 41 to permit movement of the press boxes 11, until the pulley 18 has been rotated to stop the trumper and plunger which action swings the bar from over 65 the latch to its original position shown in full lines Figure 4.

In Figures 10 to 14, I have shown a modified form of the invention. Instead of the swinging locking bar 36 and vertical shaft 34, a sliding bar 70 60 is provided. This bar is positioned to move between the stop bar 53 and the latch 44, similar to the bar 36. For imparting movement to said bar, a gear rack 61 is formed thereon and this rack is in constant engagement with a pinion 62, mounted on a suitable shaft 63. The

outer end of the shaft has the central portion of a lever 64 secured thereto, and it is obvious that when the lever is swung the shaft is rotated to move the bar 60. For swinging the lever, chains 5 65 are secured to each end thereof. The chains pass over idler pulleys 66 and have their other ends fastened to diametrically opposite sides of a collar 67 secured on the outer end of the pulley shaft 19 in place of the arm 31. It will be seen by observing Figure 13 that when the shaft 19 10 is rotated, the lever 64 is swung to rotate the shaft 63 and pinion 62, thereby moving the bar 60 inwardly or outwardly. The operation of the other parts is the same as that shown in Figures 1 to 9 and a description is deemed unnecessary. 15

What I claim and desire to secure by Letters Patent is:

1. A locking mechanism for a press box having a notch on one end thereof, including a swinging latch for engaging the notch to hold 20 the box in an immovable position, a manual operator for swinging the latch to its disengaged position, and controlling means connected with the operating means of a trumper and arranged to engage over said latch when it is engaged in 25 the notch, whereby swinging of the latch is prevented when the trumper is operated, said controlling means being disengaged from the latch when the trumper is inoperative, whereby the latch may be swung to disengage it from the 30 notch, the swinging of the latch moving said latch from the notch to a position in the path of said controlling means to prevent actuation of said controlling means and trumper.

2. A locking mechanism for a press box having 35 a bar provided with a notch on one end thereof, including a swinging latch for engaging the notch to hold the box in an immovable position, a manual operator for swinging the latch to its disengaged position, controlling 40 means connected with the operating means of a trumper and having an element arranged to engage over said latch when the latter is engaged in the notch, whereby swinging of the latch is prevented when the trumper is operated, said 45 controlling means being disengaged from the latch when the trumper is inoperative, whereby the latch may be manually swung to disengage it from the notch, and spring-pressed means arranged to move into the path of the latch engaging element of the controlling means to prevent actuation thereof when the latch is disengaged from the notch bar, thereby preventing 50 operation of the trumper when the press-box is moved from its latch engaging position. 55

3. A locking mechanism for a press box having a bar provided with a notch on one end thereof, including a swinging latch for engaging the notch to hold the box in an immovable position, a manual operator for swinging the latch to its 60 disengaged position, controlling means connected with the operating means of a trumper and having an element arranged to engage over said latch when the latter is engaged in the notch, whereby swinging of the 65 latch is prevented when the trumper is operated, said controlling means being disengaged from the latch when the trumper is inoperative, whereby the latch may be manually swung to disengage it from the notch, and a swinging 70 stop bar arranged to move into the path of the latch engaging element of the controlling means to prevent actuation thereof when the latch is disengaged from the notch bar, thereby preventing 75 operation of the trumper when the press-

box is moved from its latch engaging position, said stop bar being engaged by a member on the press box to swing said stop bar out of the path of said controlling means prior to the engagement of the latch in said notch.

4. In a press of the class described, a press box locking mechanism comprising, with a box mounted for movement into and from position for a pressing operation therein, a latch-engaging element located on the box and movable therewith to a definite latching position with the box in proper position for the pressing operation, a stationary latch mechanism having a normally yieldably urged latch element automatically engaging said latch-engaging element to hold the box when the same is brought into proper position for the pressing operation therein, means for operating the press when the box is so positioned, and an interlocking element associated with the press operating means and cooperating with the stationary latch mechanism so as to prevent release of said normally yieldably urged latch element from the latch-engaging element on the box and also preventing the operation of the press when said latch element of the mechanism is moved from said box-holding position.

5. In a press of the class described, a press box locking mechanism comprising, with a box mounted for movement into and from position for a pressing operation therein, a latch-engaging element located on the box and movable therewith to a definite latching position with the box in proper position for the pressing operation, a stationary latch mechanism having a normally yieldably urged latch element automatically engaging said latch-engaging element to hold the box when the same is brought into proper position for the pressing operation therein, manually operable means for releasing said latch element from said latch-engaging element, and controlling means associated operably with the pressing means of the press whereby to automatically lock said latch element in engagement with the latch-engaging element on the box during the pressing operation within the box and for preventing operation of the pressing means when said latch element is moved from said box-holding position.

JAMES S. NEVITT.
